UNITED STATES PATENT OFFICE.

JOHN R. TURNER, OF STOWMARKET, ENGLAND.

STAMP-AFFIXER.

SPECIFICATION forming part of Letters Patent No. 714,536, dated November 25, 1902.

Application filed June 2, 1902. Serial No. 109,993. (No model.)

To all whom it may concern.

Be it known that I, JOHN ROBERT TURNER, a subject of the King of Great Britain and Ireland, residing at Stowmarket, in the county 5 of Suffolk, England, have invented a new and useful Stamp-Affixer, of which the following is a specification.

This invention relates to an improved apparatus for applying and affixing adhesive 10 postage and like stamps to envelopes, post-cards, and other articles where stamps are now used; and it has for its object to avoid the necessity of having to moisten the stamps with the tongue or to damp them by hand and 15 at the same time to expedite the operations of applying and affixing such stamps when a number are to be used. To this end I provide an apparatus that will hold a supply of postage or like adhesive stamps piled up 20 ready for use and will allow them to be withdrawn singly, then moistened, and applied and affixed to the envelop or the like at one and the same operation.

An apparatus embodying the invention 25 comprises a magazine for the stamps, a device for lifting the uppermost stamp off the pile, a gripping device for withdrawing the lifted stamp presented thereto and pressing it against a moistening device, and a presser 30 device for holding the moistened stamp onto the envelop or the like while the gripping device releases it and retires, and for then finally affixing said stamp to the envelop or the like, the said devices being so arranged 35 and combined that by a single manual operation of the presser device all the above-mentioned functions or operations are practically effected concurrently, and in order that the said invention may be readily understood I 40 will describe the same fully with reference to the accompanying drawings, in which—

Figure 1 is a front elevation of the improved apparatus with its operative parts or devices in their normal position. Fig. 2 is a horizontal section taken on the line A A of Fig. 1. Fig. 3 is a vertical longitudinal section of the apparatus, showing the parts or devices in the position they assume when the stamp has been applied and affixed. Fig. 4 is a horizontal section taken on the line B B of Fig. 3. Fig. 5 is a front elevation showing the operative parts or devices in position to hold the

jaws of the gripping device open ready to seize a stamp. Fig. 6 is a vertical cross-section taken on the line C C of Fig. 5 looking in the direction of the arrow 6. Fig. 7 is a similar section on the same line C C of Fig. 5 as seen when looking in the opposite direction to that indicated by the arrow 6. Figs. 8, 9, and 10 show details.

The box or casing is indicated by the letter a and is constructed of any suitable material. It carries all the various devices hereinbefore mentioned. This box or casing a, which may have a glazed front or door, is mounted 65 on a stand or base-board b, to which it is advantageously hinged at c, so that it can be readily thrown back when it is desired to have access to certain of the parts, or to replenish the stock of postage-stamps, or to recharge the 70 moistening device, or for any other purpose. The bottom plate of this casing is provided with three apertures, beneath the first one of which is arranged a stamp-magazine and beneath the second one of which is arranged the 75 moistening device. The third aperture permits the passage of the stamp to the envelop or the like, which is inserted in the gap between the stand or base-board b and the bottom of said casing. Through the top of the 80 box or casing passes the stamp-lifting device, (shown detached in Fig. 8,) which consists of a hollow plunger d, (or it may be hollow at one end only,) carrying at its lower end a detachably-connected spring-controlled pair of 85 arms e, fitted with plugs or pads f of suitable material—such as felt, wool, &c.—charged with any appropriate slightly-adhesive medium for lifting the stamps g one by one, as required, from the magazine h. This latter 90 may fit into a recess formed for its reception in the stand or base-board b, or it may be supported on flanges fixed to the under side of the bottom of the box or casing. In the drawings the said magazine is shown as fitted into 95 a recess. The arms e, carrying the plugs or pads f, are advantageously arranged breadth-wise of the stamps, so as to lift each one without causing it to buckle and present it in a flat condition to the gripping device. The 100 said plunger is guided in its reciprocations by a plate or bracket i and is connected by means of a forked and slotted lever j, pivoted at k, with the presser device, so that it works

in unison therewith—that is to say, they both descend and ascend simultaneously. A spring *l* is provided to assist the upward stroke of the lifting device; but this is not absolutely necessary.

The presser device comprises a rod or stem *m*, traversing the top of the casing *a* through a guide-tube *n* and is fitted with a knob *o* to permit it to be readily operated by hand. A helical spring *p* is provided to return the presser to its normal position, as will be readily understood on reference to Figs. 1 and 3. The rod or stem *m* carries at its lower end a block or pad *q*, of rubber or other resilient material, secured to a metal plate *r*, and said plate is pivoted at *s* to the rod or stem and is normally retained at an incline thereto by the action of a spring *t*, the object of such inclination being hereinafter mentioned. On the under side of the block or pad *q* is a tooth or rib *u*, also of resilient material, to hold the stamp onto the envelop and prevent it being drawn away by the gripping device (hereinafter fully described) when completing its backward stroke.

Below the presser device is the gripping device. This consists of a sliding plate *v*, moving in longitudinal guideways *w* and carrying jaws or grippers *x x'*. The lower jaw *x* is advantageously formed in a piece with the plate *v*, while the upper jaw *x'* is pivoted thereto at *y* and is normally held closed by a spring *z*. These jaws are connected with the presser device by means of a bell-crank lever 1, one arm of which is pivoted at 2 to a pillar 3 on the sliding plate *v* and the other arm of which is pivoted at 4 to the rod or stem *m* of the presser device, and said bell-crank lever is fulcrumed at 5 in a bearing 6, secured to the inner side of the box or casing *a*. The upper jaw *x'* is provided with a cross-rod 7, adapted to ride up inclined blade-springs 8, each fixed at one end to a bracket 9, secured to the bottom of the box or casing and resting by their other or free ends upon the guideways *w*. By these means the jaws are caused to open against the tension of the spring *z* as they advance toward the stamp-lifting device. The forward upper ends of the blade-springs 8 terminate at such a distance from the stamp-lifting device as to allow the cross-rod 7 to fall off them when the open jaws have sufficiently advanced to reach and grip the stamp presented to them by the lifting device and so cause them to close by the action of the spring *z*.

10 is the aperture in the bottom of the box or casing *a*, through which the presser-block passes to apply and affix the stamp to the envelop or the like placed beneath it.

The moistening or damping device for the stamps consists of a trough 11, secured to the under side of the bottom of the box or casing (or detachably connected therewith) and fitting into a recess in the stand or base-board *b*. Said trough contains a pad 12, charged with

water, or it may contain a roller dipping into water.

Adjacent to the above-mentioned device is a curved plate 13, pivotally mounted in standards 14 and serving to press the stamps as drawn over the moistening or damping device by the jaws or grippers onto the absorbent pad or roller, so that said stamps shall be properly moistened prior to their being applied to the envelop or the like. A slot 15 is formed in the said curved pressing-plate 13 to allow passage to the spring-jaws *x x'* in their reciprocating motion.

A fastening device of any appropriate character may be provided at the end opposite the hinge, so as to lock the box or casing to its stand or base-board and prevent any one tampering with the mechanism. The casing being hinged as before mentioned will by slightly turning on its hinge allow of letters or packages of varying thicknesses to be readily inserted for applying and affixing the stamps.

The working is as follows: An envelop or the like having been placed in position with its right-hand corner under the aperture 10, the presser device is then depressed by hand so as to cause the stamp-lifting device to descend and pick up the uppermost stamp of the pile, and it is then allowed to return and permit the parts to assume the position shown in Fig. 1, the gripping device in this motion having moved backward and then advanced and gripped the stamp. At the subsequent depression of the presser device the jaws withdraw the stamp from the lifting device and carry it beneath the curved plate 13 over the pad 12, where it is moistened and is ready for application to the envelop. During the retiring motion of the gripper device its cross-rod 7 travels beneath the blade-springs 8 and so keeps the jaws closed. By the time the jaws have very nearly reached the end of their rearward travel and the stamp has thereby been brought over the aperture 10 in the bottom of the box or casing *a* the cross-rod 7 has escaped from the blade-springs 8 and the inclined presser-block *r* has moved down and brought its resilient tooth or rib *u* to bear upon the free end of the stamp, as indicated in the dotted position shown in Fig. 1. By continuing the pressure on the presser device the block or pad *q* is now brought into a perfectly horizontal position, as seen in Fig. 3, onto the stamp and so firmly and finally affixes it to the envelop. At the same time the jaws *x x'* of the gripper withdraw from the stamp and move sufficiently out of the path of the presser-block to permit this latter to become truly effective. Concurrently with the downstroke of the presser device the forked lever *l* has brought the stamp-lifter down onto the pile of stamps in the magazine *h*. Pressure now being removed from the presser device, the spring *p* returns it to its initial position and causes the gripping device to

110
115
120
125
130

again travel forward by reason of the movement imparted to the bell-crank lever 1, while simultaneously with this movement the stamp-lifter ascends, owing to its lever connection with the presser device. Immediately after the commencement of this advance travel of the gripping device the cross-rod 7 of the jaws x passes up the inclined blade-springs and so causes said jaws to open until 10 they reach the position shown in Fig. 5 ready to grip another stamp. At the moment the jaws reach the limit of their stroke and project beyond the edge of the stamp the cross-rod 7 arrives at the extremities of the blade-springs 8 and falls down, so permitting the spring z to come into action and close said jaws upon the stamp. The apparatus is now ready for another operation, and all that is necessary to do is to place another envelop or 15 the like in position and then to depress and release the presser device in a continuous manner, the intermediate motions being automatically performed by the lever mechanism forming the connection between the co- 20 acting parts of the apparatus.

Having now described my invention, what I claim, and desire to secure by Letters Patent, is—

1. An apparatus for applying and affixing adhesive postage and like stamps to envelops, 30 post-cards, and other articles, comprising a casing formed with an aperture at the bottom and means within said casing for lifting stamps singly from a pile, means for gripping and removing each stamp, means for moistening the same, means for applying and affixing said stamp, through said aperture in the casing, onto an envelop or other article placed beneath the casing, and lever mechanism for 35 interconnecting the operative parts.

2. In apparatus for applying and affixing adhesive postage and like stamps to envelops, post-cards, and other articles, the combination with a casing hinged at one end to a stand 40 or base-board, and provided with a glazed front or door, and an aperture in the bottom fitted with a magazine for holding stamps, a second aperture in the bottom to provide access to a moistening device disposed beneath 45 said aperture, and a third aperture to permit the application of the stamp to the envelop or other article placed beneath the casing, of a stamp-lifting device mounted within the casing and above the first-named aperture, a moistening device beneath and means above 50 the second aperture for pressing the stamp against the said moistening device, a gripper device, a presser device passing through the top of said casing and fitted with means for 55 operating it from the exterior, and lever mechanism for connecting said presser device with said lifting and stamp-gripping devices.

3. In an apparatus of the character described, the combination with a casing containing in its interior a moistening device, a stamp-gripping device, and a presser device, of a stamp-lifting plunger fitted at its lower

end with detachable arms carrying pads or plugs to receive an adhesive material for the purpose set forth.

4. In an apparatus of the character described, the combination with a casing containing in its interior a stamp-lifting device, a stamp-moistening device, a gripping device, and a presser device, of a stamp-lifting plunger formed with a hollow end and carrying detachable arms, and a spring in the hollow end to act on said arms.

5. In an apparatus of the character described, the combination with a casing containing in its interior a stamp-lifting device, a stamp-moistening device, a gripping device, and a presser device, of a stamp-lifting plunger engaging with a forked lever pivoted at one end to the said casing, and near its other end to said presser device, whereby said stamp-lifting device and presser device are caused to work in unison.

6. In an apparatus of the character described, the combination with a casing containing in its interior a stamp-lifting device, a stamp-moistening device, a gripping device, and a presser device, of a vertically-mounted stamp-lifting plunger guided in a plate or bracket secured to the interior of the casing and traversing the top of said casing.

7. In an apparatus of the character described, the combination with a casing containing in its interior a stamp-lifting device, a stamp-moistening device, a gripping device, and a presser device, of a trough arranged beneath an aperture in the bottom of said casing, a moistening-pad located in said trough and projecting through said aperture, and a curved plate pivoted at one end to standards fixed to said casing and resting with its lower curved end on the moistening-pad.

8. In an apparatus of the character described, the combination with a casing containing in its interior a stamp-lifting device, a stamp-moistening device, a gripping device, and a presser device, of a trough furnished with a moistening-pad arranged beneath an aperture in the casing, and a slotted curved plate above said moistening-pad pivoted to standards within the casing.

9. In an apparatus of the character described, the combination with a casing carrying in its interior a stamp-lifting device, a stamp-moistening device, a gripping device, and a presser device, of reciprocating gripper-jaws, one formed integrally with a sliding plate and the other hinged thereto, a spring to close said jaws, and a cross-rod fixed to the upper jaw for opening the jaws.

10. In an apparatus of the character described, the combination with a casing carrying in its interior a stamp-lifting device, a stamp-moistening device, a gripping device, and a presser device, of reciprocating spring-controlled jaws connected with a sliding plate and fitted with a cross-rod, and inclined blade-springs to serve as a track for said cross-rod.

11. In an apparatus of the character de-

- scribed, the combination with a casing carrying in its interior a stamp-lifting device, a stamp-moistening device, a gripping device, and a presser device, of reciprocating spring-controlled jaws connected with a sliding plate and fitted with a cross-rod, and inclined blade-springs fixed at one end to brackets carried by the casing and resting with their free ends in the guideways of said sliding plate.
12. In an apparatus of the character described, the combination with a casing carrying in its interior a stamp-lifting device, a stamp-moistening device, a gripping device, and a presser device, of reciprocating spring-controlled jaws connected with a sliding plate, and a pillar fixed to said sliding plate for moving it, and lever mechanism for actuating the operative parts in unison.
13. In an apparatus of the character described, the combination with a casing carrying in its interior a stamp-lifting device, a stamp-moistening device, a gripping device, and a presser device, of reciprocating spring-controlled jaws connected with a sliding plate provided with a pillar and a bell-crank lever connected by one arm to said pillar and by the other arm to the presser device, and fulcrumed to a bearing in the casing.
14. In an apparatus of the character described, the combination with a casing carrying in its interior a stamp-lifting device, a stamp-moistening device, a gripping device, and a presser device, of a rod or stem for said presser device, passing through the top of the casing and guided in a tube fixed to the casing, a helical spring mounted upon the outer portion of said stem, and a knob fixed to this latter.
15. In an apparatus of the character described, the combination with a casing carrying in its interior a stamp-lifting device, a

stamp-moistening device, a gripping device, and a presser device, of a stem for said presser device fitted at its lower end with a pivoted plate retained normally at an angle thereto, a spring secured in said stem and pressing with its free end on said plate, and a resilient block secured to the under side of said plate.

16. In an apparatus of the character described, the combination with a casing carrying in its interior a stamp-lifting device, a stamp-moistening device, a gripping device, and a presser device, the said presser device consisting of a spring-controlled stem guided in a tube fixed to the top of the casing, a plate pivoted to the lower end of said stem in the interior of the casing, a resilient block secured to said plate, and a resilient tooth or rib on the under side of said block.

17. A stamp applying and affixing apparatus comprising the following instrumentalities: a stamp-lifting device for removing the uppermost stamp from a pile, a gripping device for withdrawing the lifted stamp presented to it, a moistening device over which said stamp is drawn by the gripping device, and a presser device for holding the moistened stamp onto the envelop (or the like) and finally affixing it thereto, and lever mechanism combined with said instrumentalities whereby on the presser device being depressed all the said instrumentalities are operated concurrently.

In witness whereof I have hereunto signed my name in the presence of two subscribing witnesses.

JOHN R. TURNER.
